UNITED STATES PATENT OFFICE.

JERRY J. LA DUCER, OF HARTFORD, CONNECTICUT, ASSIGNOR TO PRATT & WHITNEY COMPANY, OF NEW YORK, N. Y., A CORPORATION OF NEW JERSEY.

TAILSTOCK.

Application filed April 21, 1921. Serial No. 463,274.

To all whom it may concern:

Be it known that I, JERRY J. LA DUCER, a citizen of the United States, residing at Hartford, in the county of Hartford and State of Connecticut, have invented certain new and useful Improvements in Tailstocks, of which the following is a specification.

This invention relates to tailstocks and particularly to a multiple-spindle tailstock 10 provided with means for simultaneously operating the several spindles and preferably the clamping means therefor. In the ordinary form of single spindle tailstock, the spindle is adapted to be clamped and unclamped within its bearing in the tailstock. However, in a tailstock provided with a plurality of spindles such clamping and unclamping operations would be tedious and involve considerable time in changing the 20 work. The present invention accordingly provides means for simultaneously moving all the spindles against the work, preferably with an equal pressure, and further means controlled preferably by a single operating 25 member for simultaneously effecting the clamping and unclamping of all the spindles within the tailstock. Further objects and details of the invention will appear as the description proceeds.

30 Referring to the figures of the drawing:

Figure 1 is a plan view of my improved tailstock showing certain operating parts thereof in section and other parts in dash lines.

35 Fig. 2 is a vertical sectional view taken on the line 2—2 of Fig. 1.

Fig. 3 is a side elevation partly in section on the line 3—3 of Fig. 1.

40 Fig. 4 is a fragmentary sectional view taken on the line 4—4 of Fig. 1 and showing the tailstock locking latch and a portion of its operating means.

Referring more specifically to the drawing, 1 indicates the table of a milling machine on which the tailstock is adapted to be mounted, locating pieces 2 of the tailstock base 3 fitting within one of the T-slots of the machine table. The tailstock comprises the base 3, member 4 slidably mounted on 45 the ways 5 of the base and a plurality of spindles 6 mounted within the member 4. A gib 7 secured to the member 4 by means of bolts 8 and adjustable laterally by means

of screws 9 holds the member 4 on these ways.

Any convenient means may be provided to move the member 4 on these ways. I have illustrated this means as comprising a rack 10 secured to the base 3 by means of screws 11 and engaged by a pinion 12 mounted on 55 a tubular shaft 13 journaled in the member 4. A screw 14 engages within an annular groove in a bushing 15 whereby one end of the shaft 13 is supported. The shaft may be rotated by means of a squared extension 16 pinned to the shaft at 17. Within the tubular shaft 13 and extending through the bushing 15 is a shaft 18 having a pinion 19 keyed to the inner end thereof and engaging 60 rack teeth on a latch 20 provided for holding the tailstock member 4 in its forward work-engaging position, the base 3 being provided with a hole 21 within which the latch engages. A spring 22 normally holds 65 the latch in its locking position, shown in Figs. 3 and 4. The tubular shaft 13 is provided with an arcuate slot 23 through which 70 a handle 24 on the shaft 18 extends and by which the shaft 18 and the pinion 19 may be rotated to withdraw the latch.

75 Each spindle 6 comprises a sleeve 25 mounted for a limited longitudinal movement within the member 4, the means controlling such movement comprising a bolt 25' passing through a plate 26 secured to 80 the member 4 and through a bushing 27 and a spring 28 within a counterbore 29 at the rear end of the sleeve, the bolt being threaded in the sleeve at 30. As will be seen, the spring 28 normally forces the spindle forward and such forward movement of each spindle is limited by the bolt head 25^a coming into contact with the plate 26. 31 indicates work-engaging centers mounted within the sleeves 25, and 32 illustrates a member 85 adapted to support one end of the work prior to its engagement by the centers 31.

90 The clamping means for the spindles preferably comprises a separate clamping plunger 33 for engaging each spindle with a 95 wedging action. The complementary engaging surfaces of the plunger and its spindle are tapered in a direction inwardly of the spindle and rearwardly as shown at 34 in Fig. 1 and upwardly as shown at 35 in Fig. 100 2. The plunger may be held in clamping en-

gagement with the spindles by any convenient means; however, I preferably operate the plungers in a clamping direction by an expansion spring 36 surrounding each 5 plunger and engaging a flange 37 thereon. Each plunger is thereby normally held in a closed position against its spindle. A shaft 38 is journaled in the member 4 and extends beneath the plungers 33. The portions of the shaft directly between the 10 plungers are formed into drop cams 39 adapted to engage the lower ends of the plungers. It will be seen that by turning the shaft 38 to the right (Fig. 3) by means 15 of a handle on the squared end at 40 thereof, the cams 39 will raise the several plungers out of clamping engagement with the spindles and that a continued rotation of the shaft will permit the plungers to drop off the 20 cams into clamping engagement with the spindles. The springs 36 are relatively strong and therefore snap the plungers into clamping engagement with a hammer blow whereby the spindles are securely and 25 tightly locked in position.

In operation, the base 3 is secured on the table 1 in the proper position relative to the headstock, this position being such that the springs 28 will be slightly compressed by 30 the pressure of the centers 31 against the work when the member 40 has been moved to its locked position, illustrated in Figs. 3 and 4. One end of each piece of work is adapted to be supported by the member 32 35 which is notched to hold the piece in alignment with the adjacent center 31. As the member 4 is moved forward by turning the shaft 13, the centers engage the work and force the same into the headstock chucks, 40 the springs 28 yielding when the work engages the usual stop in the chuck. With the work thus held in the chucks, the cam shaft 38 is turned to the right (Fig. 3) whereupon the plungers 33 drop off the cams 39 and lock 45 the spindles in work-engaging position. The release of the tailstock and work is effected by operating the shafts 18, 13 and 37 as is believed to be obvious from the above description.

50 What I claim is:

1. A tailstock comprising the combination of a base, a spindle-supporting member mounted on the base, a plurality of work-engaging spindles mounted in the member, 55 a single controlling means for clamping and unclamping the spindles relative to the member, and means for bodily moving the member on the base longitudinally of the spindles.

60 2. A tailstock comprising the combination of a base, a spindle-supporting member mounted on the base, a plurality of work-engaging spindles mounted for a limited longitudinal movement in the member, a 65 single controlling means for clamping and

unclamping the spindles relative to the member, means for bodily moving the member on the base longitudinally of the spindles, and means for locking the member in work-engaging position on the base. 70

3. A tailstock comprising the combination of a base, a spindle-supporting member mounted on the base, a plurality of work-engaging spindles mounted for a limited longitudinal movement in the member, separate means for clamping each spindle in work-engaging position in the member, a single hand operated means for operating all the clamping means, and means for bodily moving the member on the base longitudinally of the spindles. 75

4. A tailstock comprising the combination of a base, a spindle-supporting member mounted on the base, a plurality of work-engaging spindles mounted for a limited longitudinal movement in the member, a locking plunger adapted to engage each spindle to clamp the same in work-engaging position in the member, cam means for operating the plungers, a single hand operated means for operating the cam means, and means for bodily moving the member on the base longitudinally of the spindles. 80

5. A tailstock comprising the combination of a base, a spindle-supporting member mounted on the base, a plurality of work-engaging spindles mounted for a limited longitudinal movement in the member, each spindle being provided on its exterior with a clamping surface tapered in an inward direction rearwardly and upwardly of the spindle, a locking plunger provided with a complementary clamping surface adapted to engage the clamping surface of each spindle to clamp the same in work-engaging position in the member, cam means for operating the plungers, a single hand operated means for operating the cam means, and means for bodily moving the member on the base longitudinally of the spindles. 95

6. A tailstock comprising the combination of a base, a spindle-supporting member mounted on the base, a plurality of work-engaging spindles mounted for a limited longitudinal movement in the member, a 100 spring engaging each spindle for normally holding the same in a forward work-engaging position, separate means for clamping each spindle in work-engaging position in the member, a single hand operated means for operating all the clamping means, and means for bodily moving the member on the base longitudinally of the spindles. 105

7. A tailstock comprising the combination of a base, a spindle-supporting member mounted on the base, a plurality of work-engaging spindles mounted for a limited longitudinal movement in the member, a spring engaging each spindle for normally holding the same in a forward work-engag- 110

- ing position, adjustable means for limiting the forward movement of the spindles, separate means for clamping each spindle in work-engaging position in the member, a 5 single hand operated means for operating all the clamping means, and means for bodily moving the member on the base longitudinally of the spindles.
8. A tailstock comprising the combination of a base, a spindle-supporting member mounted on the base, a plurality of work-engaging spindles mounted for a limited longitudinal movement in the member, spring-pressed means adapted to normally 10 engage the spindles to clamp the same in a work-engaging position in the member, a single hand operated means for unclamping the last named means, and means for bodily moving the member on the base longitudinally of the spindles.
9. A tailstock comprising the combination of a base, a spindle-supporting member mounted on the base, a plurality of work-engaging spindles mounted for a limited 15 longitudinal movement in the member, a spring-pressed locking plunger adapted to normally engage each spindle to clamp the same in work-engaging position in the member, a cam for releasing the locking engagement of each plunger from its spindle 20 against the action of its spring, a single hand operated means for operating all the cams, and means for bodily moving the member on the base longitudinally of the spindles.
10. A tailstock comprising the combination of a base, a spindle-supporting member mounted on the base, a plurality of work-engaging spindles mounted for a limited 25 longitudinal movement in the member, a spring-pressed locking plunger adapted to normally engage each spindle to clamp the same in work-engaging position in the member, a cam for releasing the locking engagement of each plunger from its spindle 30 against the action of its spring, a single hand operated means for operating all the cams, and means for bodily moving the member on the base longitudinally of the spindles.
11. A tailstock comprising the combination of a base, a spindle-supporting member mounted on the base, a plurality of work-engaging spindles mounted for a limited 35 longitudinal movement in the member, separate means for clamping each spindle in work-engaging position in the member, a single hand operated means for operating all the clamping means, a rack and pinion for bodily moving the member on the base longitudinally of the spindles, and means for locking the member in work-engaging position on the base.
12. A tailstock comprising the combination of a base, a spindle-supporting member mounted on the base, a plurality of work-engaging spindles mounted for a limited 40 longitudinal movement in the member, separate means for clamping each spindle in work-engaging position in the member, a single hand operated means for operating all the clamping means, a rack and pinion for bodily moving the member on the base longitudinally of the spindles, a latch for locking the member in work-engaging position on the base, and means exterior of the member for operating the latch.

In testimony whereof, I hereto affix my 45 signature.

JERRY J. LA DUCER.
